(57) **CLAIM**

The ornamental design for gear set as shown and described.

DESCRIPTION

FIG. 1 is a right side perspective view of a gear set in accordance with the invention;

FIG. 2 is a left side perspective view of the gear set of FIG. 1;

FIG. 3 is a front view of the gear set of FIG. 1;

FIG. 4 is a bottom view of the gear set of FIG. 1;

FIG. 5 is a right side view of the gear set of FIG. 1; and, FIG. 6 is a left side view of the gear set of FIG. 1.

Note that top and rear views are deemed to be identical to the view shown in FIG. 3.

Note also that the broken lines in FIGS. 4 and 6 represent portions of the device which do not form part of the claimed design.
